UNITED STATES PATENT OFFICE.

BERNARD J. HAUSFELD, OF CINCINNATI, OHIO, ASSIGNOR, BY MESNE ASSIGNMENTS, TO THE LUNKEN WINDOW COMPANY, OF CINCINNATI, OHIO, A CORPORATION OF OHIO.

ROLLER SPRING CONTROL.

Application filed December 17, 1919. Serial No. 345,493.

To all whom it may concern :

Be it known that I, BERNARD J. HAUSFELD, a citizen of the United States, and a resident of Cincinnati, in the county of Hamilton 5 and State of Ohio, have invented certain new and useful Improvements in Roller Spring Controls, of which the following is a full, clear, and exact description, reference being made to the accompanying 10 drawing, forming part of this specification.

My invention relates to devices for supporting and turning up the central or spring shafts of shade rollers and the like, although this is not the only possible application of 15 the essentials of my invention.

Among other objects of my invention is a simple means for engaging the squared end on the spring shaft of a shade roller to support the said shaft, and at the same time 20 revolve it. In this connection also, it is my object to provide a ratchet device which holds the shaft engaging means from revolution so as to preserve tension on the spring.

It has not been considered necessary to 25 show the construction of a shade roller and its shaft, since any acceptable form of spring roller is adaptable to my invention. It will be noted that the usual form of shade roller has a central shaft which has thereon a 30 spring device that is connected to the roller, thereby causing the roller to revolve, when the shaft is held. In addition to this, there is ordinarily a pair of spring pawls or the like which prevent the rotation of the roller 35 on the shaft in certain positions.

My device, as above noted, is particularly designed for application to said spring shaft, and is to be employed to wind up the shaft while retaining the roller in a fixed position, 40 thereby increasing the tension of the spring.

My various objects I accomplish by that certain construction and arrangement of parts to be hereinafter more specifically pointed out and claimed.

45 In the drawing,

Figure 1 is a perspective view of my invention shown as applied to a shade roller in a window.

Figure 2 is a detail longitudinal section, 50 taken through the parts of the device, detached.

Figure 3 is a face view of the ratchet or pawl device removed.

Figure 4 is a perspective detail of the device detached.

As shown in Figure 1, my roller spring control is employed as a means for controlling the tension in a shade roller when used as an awning. Thus the device is shown at A, at the upper end of a frame 1, and as 60 supporting a shade roller 2. There need be but one of my appliances for each roller, since, according to accepted practice, the roller shaft is supported at one end in a mere round socket.

65 I provide a mounting plate 3, having a flange 4 for attachment to a window, and an ear 5 for attachment of the remaining parts of the invention. The plate or bracket is provided with a slot 6 running in from 70 the edge thereof, to a central opening 7, said slot facilitating the tipping of the end of the roller shaft into the slotted end of the stub shaft to be described.

75 Thus there is a stub shaft 8 having a slotted end 9 to receive the flattened end 10 of a shade roller shaft 11. This shaft has pinned to the outer end thereof an operating handle 12, which may be of any desired design. A securing bracket piece 13 is mounted loosely 80 over the stub shaft inside of the operating handle, and fast to the shaft inside of the piece 13 is a special ratchet 14.

85 In mounting the parts last described on the mounting plate 3, the piece 13 is screwed at 15 to the outside of the said plate.

Pivotedly held on the piece 13 is a special double pawl or segment pawl 16, which bears against the ratchet 14. The ratchet has its teeth 17 with their apices spaced apart very 90 slightly greater than the span of the double pawl, so that when one tooth is about to leave the one end of the pawl, the approaching side of the other tooth is in engagement with the other end of the pawl.

95 From such a structure results a positive, self-locking pawl and ratchet motion. The ratchet teeth are inclined in a counterclockwise direction, and a clockwise rotation of the ratchet will permit the teeth to ride under the pawl and lift it readily from engagement. Any rotation of the ratchet counterclockwise will result in the raising up of one end of the pawl, thus forcing the other end behind the next advancing tooth, thereby positively locking the pawl in retaining position.

100 So far as I am advised, this pawl and ratchet motion is entirely novel, and provides for a device which is on the dividing 110

line between a pawl and ratchet of accepted practice and an escapement device.

In connection with a shade roller shaft holder, it provides against any chance of the spring of the roller jerking so quickly at the pawl that it slips by the ratchet and allows the roller spring to become loose. Without some such automatically locking device, with positive motion, a device for 10 winding up the spring on a shade roller shaft could not be entirely practical.

My whole device is simply replaced for the usual slotted bracket plate that holds fast the squared end of a curtain shade roller, and is simple and inexpensive, and easy 15 to operate, without any danger of having the said roller shaft spin out of control.

I do not desire that the claims that follow be limited beyond the natural scope of their 20 language, because of my failure above to refer to possible mechanical equivalents for the structure described.

Having thus described my invention, what I claim as new and desire to secure by Letters Patent, is:—

1. In a device of the character described, a

mounting plate adapted to be mounted on the desired framework, and having a slot therein, and an aperture communicating with said slot, a shaft extending through 30 said aperture and having a slotted end, a plate mounted over the said shaft and secured to the mounting plate, said plate carrying a pawl, and a ratchet 35 over which said pawl rests, said ratchet mounted on the said shaft.

2. In a device of the character described, the combination with a mounting element, means for revolvably retaining therein a member to receive a shade roller shaft end, 40 and means thereon for stopping the motion of the said revolvable means except in one direction, said stopping means comprising a ratchet and double-ended pawl arranged in a position to straddle the ratchet, with the 45 ratchet teeth having apices spaced apart just slightly greater than the ends of the pawl, and shaped to pass under the pawl in one direction, but to raise one end of the pawl and jam it behind the next advancing tooth, 50 upon reverse direction.

BERNARD J. HAUSFELD.
